Attorney

UNITED STATES PATENT OFFICE.

GEORGE J. HARBEES, OF LEONARDVILLE, KANSAS.

STORAGE-BATTERY-SWITCH LOCK.

Application filed March 20, 1922. Serial No. 545,179.

To all whom it may concern:

Be it known that I, GEORGE J. HARBEES, a citizen of the United States, residing at Leonardville, in the county of Riley and

5 State of Kansas, have invented a new and useful Storage - Battery - Switch Lock, of which the following is a specification, reference being had to the accompanying drawings, which are hereby made a part hereof.

10 My invention relates to appliances for the protection of automobiles from theft and the objects are:—To prevent short circuiting of the battery, to provide an effective device for shutting off and locking the switch connection with the battery and to prevent tampering with the ignition and lighting system.

15 These objects I accomplish by the mechanism hereinafter described and illustrated in the accompanying drawing in which:—

20 Fig. 1 is a face view of the instrument-board of an automobile with my device attached;

25 Fig. 2, a longitudinal sectional view of my device in locked position;

Fig. 3, a view of the same in unlocked position;

30 Fig. 4, a cross-sectional view, on line 4—4 of Fig. 2, of the head, exposing the lock-bar and spring actuating the same;

Fig. 5, a cross-sectional view, on line 5—5 of Fig. 2, exposing the lock-bar in locked position;

35 Fig. 6, a detail sectional view, on line 6—6 of Fig. 3, of the mushroom and the surrounding parts.

Similar numerals of reference indicate like parts thruout the several views.

1, represents the instrument board of an 40 automobile; 2, the casting by means of which my device is secured in position; 3, the outer section of the main sleeve; 4, the inner section of said sleeve; 5, the bottom or end cap; 6, insulation fiber; 7, spring;

45 8, sleeve to lower end of plunger-rod 9; 10, threaded portion of plunger-rod; 11, mushroom contacts; 12, securing nuts; 13, sleeve of insulation; 14, flange to said sleeve; 15, lock-nut; 16, outer end of plunger-rod 9;

50 17, insulation bushing; 18, knob; 19, annular groove; 20, lock-bar; 21, notch; 22, lock-bar operating rod; 23, knob; 24, spring actuating lock-bar when released; 25, head; 26, screw-plug; 27, notch in bar 20; 28, locking-plug; 29, cutaway part; 30, lock; 31 and 32, terminals; 33, positive electric wire; 34,

negative wire; 35, insulation sleeve; 36, slots; 37 and 38, copper plates.

My device is constructed in the following manner:—

60 A casting 25, bored thru to receive a plunger-rod 9, has threaded portion 10 bearing lock-nut 15. The inner end of said plunger-rod is slidably seated in sleeve 4. Suspended on said plunger-rod by means of 65 securing nuts 12 is a mushroom having contacts 11 within said sleeve 3—4 made in two sections as shown. Copper plates, or other conductive material, 37 and 38 attached to terminals 31 and 32 are inserted 70 within said sleeve 3—4 in contact with said mushroom when the switch is in closed position. One of such plates extends beyond the other so as to retain contact with the mushroom and ground the electric current 75

when the switch is open and prevent starting the car or tampering with the ignition. The terminal on the battery side of the switch being in contact with the shorter conductive plate, when the plunger-rod is 80 pushed in into locked position, as shown in Fig. 2, the electric current from the battery is entirely cut off, thus avoiding and absolutely preventing any danger of the car catching fire from short circuiting of such 85 electric current. Any attempt, while such switch is in locked position, to use any other means, such as another battery or dry batteries, by connecting the same with such terminals would be futile because the current 90 therefrom would be instantly grounded and useless.

Between said copper plates and the sleeve 3—4 I place insulation pads 35 and a pad 6 is placed on the inside of cap 5 between it and spring 7. Terminals 31 and 95 32 are secured to plates 37 and 38 and stiffened and steadied by passing thru plugs or nuts entering said main sleeve 3—4. When the plunger-rod 9 is pushed in, as shown in Fig. 2, the mushroom contacts 11 are 100 switched off and the electric current can only enter on the side where the copper plate extends beyond the point of contact, and thence passes thru the plunger-rod 9 to ground connection. When the plunger-

105 rod is released spring 7 forces the mushroom into contact, as shown in Fig. 3. Electric current may be communicated from the storage battery thru wires 33 and 34 attached to terminals 31 and 32, as shown in Fig. 2 110 or thru electrodes attached to such terminals or in any other serviceable manner.

The locking arrangement is accomplished by means of the head 25, provided with a threaded flange, secured to the outer end of main sleeve 3—4. Extending into this head 5 is a lock-bar 20, secured to operating rod 22, with a knob 23 on its exposed end and a spring 24 behind such lock-bar held in place by a screw-plug 26. The head 25 spreads out to form a plate or casting by 10 means of which it is secured in position on the instrument-board, foot-board or wherever it is desired to place it. The plunger-rod 9 is provided with an annular groove 19 into which lock-bar 20 is seated when the 15 switch is in locked position. An ordinary Yale or other combination lock 30 is so placed in said head 25 as when turned to locked position serves to retain said lock-bar and consequently such switch in such 20 locked position until released by turning of the key and the release of said lock-bar 20, which is forced out by spring 24 when knob 18 is pushed inward.

A sleeve of insulation fiber 13 having 25 flange 14 of like material is inserted between such plunger-rod 9 and the casting and held in position on such plunger-rod by means of nut 15, and a similar insulation sleeve 17 is inserted at the outer end of said head between it and said plunger-rod.

Some of the advantages of my invention are:—Prevents short circuiting of the electric current and consequent danger of fire therefrom and prevents theft of the car by 35 grounding the electric current in the event of any attempt to connect up other wires or another battery with the ignition system while the switch is open and locked, as described.

Having thus described my invention what I claim as new and desire to secure by Letters Patent is,—

1. In an electric switch, the combination with two separate conducting contact studs 45 of a conducting member mounted upon a longitudinally movable shaft, an engaging means disposed on said shaft, said conducting member normally connecting the two contact studs, the conducting member being 50 movable away from one of the contact studs, means engaging said shaft to move said conducting member into engagement with the contact studs, means for locking said

conducting member in its inoperative position, said means comprising a locking-bar 55 engaging said engaging means on said shaft and a locking-plug co-operating with the locking bar for locking said bar and shaft when the conducting member is disconnected.

2. In an electric switch, the combination with two separate conducting contact studs of a conducting member mounted upon a longitudinally movable shaft, an engaging means disposed on said shaft, said conducting member normally connecting the two contact studs, the conducting member being movable away from one of the contact studs, means engaging said shaft to move said conducting member into engagement 70 with the contact studs, means for locking said conducting member in its inoperative position, said means comprising a locking-bar engaging said engaging means on said shaft, a locking-plug co-operating with the locking bar for locking said bar and shaft, and means for automatically disengaging said locking-bar from said shaft when said locking-plug is released.

3. In an electric switch, the combination 80 with two separate conducting contact studs of a conducting member mounted upon a longitudinally movable shaft, said member comprising a plurality of resilient members 85 disposed concentrically with respect to said shaft and conductively secured at one of their ends to said shaft, an engaging means disposed on said shaft, said conducting member normally connecting the two contact studs, the conducting member being 90 movable away from one of the contact studs, means engaging said shaft to move said conducting member into engagement with the contact studs, means for locking said conducting member in its inoperative position, said means comprising a locking-bar 95 engaging said engaging means on said shaft and a locking-plug co-operating with the locking bar for locking said bar and shaft when the conducting member is disconnected.

GEORGE J. HARBES.
